UNITED STATES PATENT OFFICE.

FREDERICK A. SCHULTZ, OF HASBROUCK HEIGHTS, NEW JERSEY, ASSIGNOR
TO MATTSON RUBBER COMPANY, OF NEW YORK, N. Y., A CORPORATION
OF NEW YORK.

DRESS-SHIELD.

SPECIFICATION forming part of Letters Patent No. 726,357, dated April 28, 1903.

Application filed June 15, 1901. Serial No. 64,644. (No model.)

To all whom it may concern:

Be it known that I, FREDERICK A. SCHULTZ, a citizen of the United States, residing at Hasbrouck Heights, in the county of Bergen and State of New Jersey, have invented a certain new and useful Improvement in Dress-Shields, of which the following is a description.

My invention relates to improvements in seamless dress-shields of rubber or other suitable material. At the present time it is the practice in the manufacture of these articles to either cut out the shields from separate sheets of raw or unvulcanized rubber and subsequently apply pressure adjacent to the armpit-curves of several pairs of the blanks thus formed, after which the shields so produced are vulcanized, or else to effect the binding of the sheets at the armpit-curves simultaneously with the cutting of the same. The resulting articles will be formed with a seam at the armpit, which is a source of weakness. It frequently happens in the manufacture of the shields that the sheets vary slightly in thickness at different points, due to imperfections in the calendering operation, so that in the application of pressure to effect the seam at the armpit-curves the thinner portions of the sheets do not effectively adhere together, thereby resulting in an imperfect seam. Another defect frequently encountered in the carrying on of the prior processes has been due to the fact that the powder with which the sheets are coated to prevent them from sticking together in the raw state tends to prevent the formation of a perfect and coherent joint at the seam, in consequence of which the proportion of shields to be rejected is increased. With prior processes it is also the practice, after the shields have been vulcanized, to trim the edges to the desired sizes. Hence the rejected scraps will be vulcanized, and consequently of little value in comparison with that of raw or uncured rubber.

The object of my present invention is to produce a dress-shield of rubber or other suitable material which shall be free of all seams and joints and in which the material at no part will be in a distorted or stretched con-

dition. My improved dress-shield when made of rubber in an unvulcanized condition will be also of such a construction that it may be readily trimmed to any desired size, permitting a trimming in the raw state and securing in this way "scraps" which are unvulcanized, and hence of the maximum value. My improved shield is preferably corrugated to increase its capacity for radiation, so that the resulting article in its preferred form will be very much cooler and more comfortable than shields of analogous types at present on the market.

In order that the invention may be better understood, attention is directed to the accompanying drawings, forming part of this specification, and in which—

Figure 1 is a side view of the preferred former employed in the manufacture of the shields; Fig. 2, a section on the line 2 2 of Fig. 1; Fig. 3, a section on the line 3 3 of Fig. 1; Fig. 4, a corresponding section illustrating a modification in the arrangement of the corrugations on the former, and Fig. 5 a perspective view of the complete seamless rubber dress-shield in its preferred form.

In all of the above views corresponding parts are represented by the same numerals of reference.

1 represents a former made of any suitable material, having an armpit-curve at its upper end and of any desired form on its outer edge. This former is operated in any suitable way—as, for example, by a rod 2. On each side the former is provided with guide-slots 3 3, extending from one end of the armpit-curve to the other and corresponding to the several standard sizes in which the shields are made. Preferably the formers are vertically corrugated, as shown at 4. These corrugations may oppose each other, as shown in Fig. 3, in which case the resulting shield will be formed with opposing flutes, or the corrugations may coincide with each other, as shown in Fig. 4, in which case the two sides of the resulting shield will extend substantially parallel, as will be understood.

In manufacturing my improved dress-shield I proceed substantially as follows: A suitable solution, formed by dissolving pure

rubber or other material in a suitable solvent, is sustained in any desired tank or receptacle and the former I dipped therein with the armpit-curve downward. The former is then removed and the solvent permitted to evaporate, leaving a thin film or pellicle of rubber or other material on the former. This operation is repeated until a layer of sufficient thickness is obtained. By means of a knife or other instrument the resulting shield will be cut along the line of one of the guides 3 to the desired size, after which the film or pellicle is peeled off of the former and the shield, if made of rubber, is then vulcanized, or the vulcanization may be performed while the film is adhering to the former. The resulting article is then covered in the usual way with the desired fabric. My improved shield will obviously be formed with corrugations 6, corresponding to the corrugations 4. At the armpit-curve the shield will be entirely continuous and free of any joints or seams, while at all parts the shield will be free of stress or tension.

Having now described my invention, what I claim as new, and desire to secure by Letters Patent, is as follows:

1. An improved blank for dress-shields comprising uncured rubber or other suitable material in continuous dress-shield form, provided with markings thereon indicative of a plurality of sizes and along which the blank may be cut to form a dress-shield of the desired size, substantially as set forth. 25

2. As a new article of manufacture, a seamless dress-shield continuous at the armpit-curve, free of seams and joints, and with none of its portions in a condition of stress or tension, and curved markings formed in the shield extending from one end of the armpit- 30 curve to the other, substantially as set forth. 40

This specification signed and witnessed this 10th day of June, 1901.

FREDERICK A. SCHULTZ.
